UNITED STATES PATENT OFFICE.

EUGENE A. DE MAY, OF RICHMOND, TEXAS.

CAR-COUPING.

SPECIFICATION forming part of Letters Patent No. 364,494, dated June 7, 1887.

Application filed March 17, 1887. Serial No. 231,281. (No model.)

To all whom it may concern:

Be it known that I, EUGENE A. DE MAY, of Richmond, in the county of Fort Bend and State of Texas, have invented a new and Improved Car-Coupling, of which the following is a specification, reference being had to the annexed drawings, forming a part thereof, in which—

Figure 1 is a perspective view showing the application of my improved car-coupling to a car, and Fig. 2 is a horizontal section taken on line xx in Fig. 1.

Similar letters of reference indicate corresponding parts in both views.

15 The object of my invention is to provide a simple and effective device for automatically coupling cars of varying heights, and also to provide devices for uncoupling the cars without the necessity of going between them.

20 My invention consists in a spring-pressed hook attached to or formed upon a rock-shaft extending to the top of the car, and provided with a hand-wheel, by which it may be turned.

25 It also consists in the combination, with the hook, of a rod connected thereto and extending to the side of the car, for uncoupling the car from the ground.

30 In the draw-bar A, carried by the car A', and in the arm B, projecting from the top of the car, is journaled a rock-shaft, C, carrying at its lower end a hook, D, having a rounded notch, a, and a rounded nib, b. Surrounding the shaft C is a spiral-spring, E, which rests upon the draw-bar A and presses upward against a nut, 35 F, on the shaft C. The upper end of the shaft C is provided with a hand-wheel, G, by means of which it may be turned from the top of the car.

35 The extremity of the hook D is beveled from the top downward, to facilitate its engagement with a similar hook carried by a higher car. An ear, c, projects from the back of the hook D, which is pivoted to the end of a rod, d, extending through a guide, e, at the end of the

car, near the side thereof, and provided with a handle, f, and upon the rod d, between the guide e and hook D, is placed a spring, g, which tends to push the hook forward.

The hooks D of two adjoining cars engage each other, as shown in Fig. 2. When the hook 50 of one car is to be brought into engagement with a hook which is carried lower by the adjacent car, the rock-shaft C will be pushed downward against the pressure of the spring E. The notch a and nib b of the hook are of 55 such form as to be worn uniformly and in the same shape by use.

When it is desired to uncouple the cars from the top of the cars, the hooks D are thrown back by turning the hand-wheel G, and when 60 it is desired to uncouple the cars from the ground the hooks D are drawn backward by means of the rod d.

It is obvious that my improved coupler can be applied to the ordinary draw-bar, thereby 65 saving the expense and delay of making and fitting a new draw-bar.

Having thus fully described my invention, I claim as new and desire to secure by Letters Patent—

1. In a car-coupling, the combination of the shaft C, provided with the nut F and carrying the hook D, the spring E, resting upon the draw-bar A and pressing against the under surface of the nut F, and the spring-actuated 70 rod d, substantially as described.

2. In a car-coupling, the combination of the shaft C, the hook D, carried thereby, and provided with a beveled end, the spring E, the nut F, the hand-wheel G, the rod d, the guide e, and the spring g, placed on the rod between the guide e and hook D, substantially as described.

EUGENE A. DE MAY.
